CHARLES KAMPFMAN, OF EAST HARTFORD, CONNECTICUT

CIGARETTE PACKAGE

Application filed September 6, 1928. Serial No. 304,324.

An important object of the present invention is to effect a simple improvement in cigarette packages, which will facilitate the withdrawal of cigarettes when they are needed and prevent them from falling out of the opened package when they are not needed.

Other objects will appear hereinafter.
In the drawings:

Fig. 1 is a perspective view of the improved package in closed or sealed condition;

Fig. 2 a fragmentary perspective view showing the package partly opened;

Fig. 3 a vertical longitudinal section 15 through the package, showing the manner of withdrawing the cigarettes;

Fig. 4 a perspective view of a pack of cigarettes mounted in the clip forming part of the invention;

20 Fig. 5 a fragmentary face view of the main wrapper of the package unfolded; and

Fig. 6 a similar view of the outer or label wrapper of the package unfolded.

The package includes an outer main 25 wrapper 1. This wrapper is formed of two sheets of thin paper 2 and a sheet 3 preferably of tin foil interposed between the sheets 2 and co-extensive with them. The wrapper 1 is folded and sealed to form a container 30 or covering for a flat pack of cigarettes and form a package of the usual shape and size. Each paper sheet 2 is formed with two parallel lines of perforations 4. These perforated lines of the two sheets are in register 35 through the thickness of the wrapper and they define a relatively narrow strip 5 which is adapted to be torn out to open the package. At the ends of the strip 5 the two sheets 2 are cut to form two free pulling

40 tabs 6. The location and proportions of the strip are such that when the wrapper is folded and sealed in package form the strip extends transversely across the center of the upper end of the package and a short distance down the opposite faces thereof. The foil sheet 3 is unperforated so that it closes the perforations 4 of the sheets and protects the cigarettes.

Extending entirely around the main wrapper 1 is an outer or label wrapper 7. The

latter is preferably in the form of a straight strip of stout paper having a width substantially equal to the height of the package. At its upper edge it is formed with two deep notches 8 so shaped and disposed that they expose the downwardly extending ends of the strip 5 with the pull tabs 6 at opposite faces of the package. The wrapper 7 bears the package labels and is held wrapped and in place by pasting or otherwise.

Within the wrapper 1 is a clip in which the pack of cigarettes is disposed. The clip is formed of a flat strip 9 of pasteboard or other relatively stiff sheet material creased at intermediate points to bend easily, and folded into substantially U form. This provides the clip with a flat bottom portion 10 to bear against the lower ends of the cigarettes, and upstanding side portions or ends 11. The width of the strip 9 corresponds to the thickness of the pack, and the bottom portion 10 of the clip corresponds in area to the end of the pack and snugly fits the bottom of the wrapper 1. The sides 11 of the clip are somewhat shorter than the cigarettes and bear against the opposite sides of the pack. When the latter is complete the sides 11 extend straight up and down and contact with the inner side faces of the wrapper 1. Notches 12 are formed in the side members 11 adjacent the upper free ends thereof, and a light rubber band passes through said notches and surrounds the free ends of the clip and the pack. This band tends to contract the clip and compress the cigarettes toward the center of the package and into endwise alinement with the strip 5.

The package is preferably enclosed by an outer sealed envelope 14 of transparent paper. When the package is to be opened the envelope is torn off to uncover the strip 5, and either one of the free tabs 6 is grasped and pulled outwardly to tear out the strip 5. This leaves an opening extending across the end of the package and down the opposite faces thereof, and exposes the upper ends of the cigarettes at the center of the pack so that they may be withdrawn. The extension of the opening down the opposite faces

of the package enables the cigarettes to be readily grasped and withdrawn without mutilating them. As the central cigarettes are withdrawn the rubber band 13 immediately contracts the clip 9 and compresses the pack to close the gap. This automatically disposes other cigarettes at the center of the package in alinement with the opening for withdrawal. Each time that a gap is made by the withdrawal of one or more cigarettes the said contraction of the clip takes place. The pressure of the clip is equal upon opposite sides of the clip so that all of the cigarettes are successively presented to the central opening as the package 10 is emptied. While the cigarettes may be readily withdrawn when needed they are frictionally held by the rubber band and the clip with sufficient firmness to prevent them from dropping through the discharge 20 opening when they are not needed. This corrects an annoying fault in existing cigarette packages.

While I have shown and described a very desirable and commercially practicable form of my invention, I do not wish to be limited strictly to this disclosure but reserve the right to make such changes as will lie within the scope of the claims.

30 What I claim is:

1. A cigarette package comprising a wrapper to enclose a pack of cigarettes; a substantially U-shaped clip within the wrapper comprising a relatively stiff strip bearing against opposite sides of the pack and against one end thereof, said clip being bendable at the corners of the pack; and a rubber band surrounding the pack and the clip adjacent the free ends of the latter and 35 exerting a compression through the clip tending to force the cigarettes laterally toward the center of the package.

2. A cigarette package comprising a wrapper and an enclosed pack of cigarettes; a substantially U-shaped clip within said wrapper embracing the pack longitudinally of the cigarettes and comprising a relatively stiff strip of a width substantially equal to the thickness of the pack, extending 40 across one end of the pack and along opposite sides thereof and being bendable at the corners of the pack; and a resilient strand connecting the free end portions of the clip and tending to compress the pack laterally 50 through the medium of the clip.

3. A cigarette package comprising a wrapper; and a unit enclosed by said wrapper, formed independently thereof, and comprising a pack of cigarettes, an upwardly opening clip formed to engage opposite sides of the pack, and resilient means combining with said clip to transversely surround the pack and hold the cigarettes in packed relation and tending to contract the clip to transversely compress the pack and

press the cigarettes laterally into a predetermined position.

4. A cigarette package comprising a wrapper; and a unit enclosed by said wrapper, formed independently thereof, and comprising a pack of cigarettes, an upwardly opening clip formed to engage opposite sides of the pack and formed to stiffen and hold the bottom of the wrapper to normal original dimensions and shape, and resilient means combining with said clip to transversely surround the pack and hold the tops of the cigarettes in packed relation and tending to contract the clip at its upper ends.

75 80 In testimony whereof I hereunto affix my signature.

CHARLES KAMPFMAN.
